UNITED STATES PATENT OFFICE.

ALFRED S. MARLOW, OF LINCOLN PARK, NEW JERSEY.

PUMPING MECHANISM.

Application filed July 20, 1925. Serial No. 44,726.

This invention relates to pumping mechanism and more particularly it relates to diaphragm pumps.

An object of this invention is to provide an improved valve arrangement for a pump.

A second object of the invention is to provide an improved ball valve for a diaphragm pump. Other objects will be apparent from the detailed description of the invention hereinafter given.

The specific form of this invention which has been chosen for illustrative purposes resides in the ball valve chamber of a diaphragm pump. In such a pump it is customary to provide a ball which in one position closes an inlet opening, and in a second position is removed from the inlet opening a sufficient distance to enable water or other fluid to pass into or out of the pipe, the ball alternately between these two positions under the operation of the diaphragm. In accordance with this invention guiding means integral with the inner walls of the valve chamber are provided for limiting the ball to a definite path between its two maximum positions, while insuring that the ball will always tightly close the inlet opening at the proper time. As the pump of this invention is especially intended to handle raw sewage which normally contains rags, hair, string and other solid matter, the interior of the ball valve chamber along with the guiding means is fashioned in such a manner as to reduce to a minimum the presence of sharp projections which would tend to catch and hold rags, string or other solid matter in the water and cause the valve chamber to become clogged and consequently inoperative.

This invention will be better understood by reference to the following detailed description taken in connection with the accompanying drawings in which Fig. 1 is a sectional view of this invention applied to a diaphragm pump;

Fig. 2 is a top view of the same also in section; and

Fig. 3 illustrates how the cover of the ball chamber of the pump may be hinged.

Referring to the drawings, more particularly to Fig. 1, a portion of a diaphragm pump is disclosed in sufficient detail to describe the invention. The usual flexible diaphragm 3 is shown at the upper part of a horizontal chamber 4. The edges of the diaphragm are suitably clamped as shown

at the point 5, while at the center of the diaphragm the rod or arm (not shown) for operating the diaphragm is suitably fastened to the two plates 6 and 7 located on opposite sides of the diaphragm. The diaphragm chamber 4 is suitably connected by a short pipe 8 to the valve chamber 9. The chamber 9 contains a ball valve comprising a ball 10 which in its lowermost position is designed to completely close the valve seat 20 which constitutes the upper end of an inlet pipe 11. It will, of course, be understood that when diaphragm 3 is in its lowermost position the ball 10 will be firmly seated on the valve seat 20, while the movement of diaphragm 3 to its upper position will by suction cause liquid in pipe 11 to lift ball 10 away from the valve seat 20 and allow the liquid to flow through pipe 8 into the diaphragm chamber 4. The return of the diaphragm 3 to its lower position will cause ball 10 to close pipe 11 again so that the liquid in chamber 4 will be forced on beyond the chamber 4 to any suitable outlet or reservoir. It will, of course, be understood that if desired another ball valve may be provided between the chamber 4 and the outlet which will be opened when the diaphragm 3 is being pushed downwardly to force out the water.

In the upward and downward movement of the ball 10 corresponding to the operation of diaphragm 3, it is essential that its path be clearly defined so as to limit the sidewise motion of the ball and insure its return each time in such a manner as to secure the prompt closing of pipe 11. In accordance with this invention a plurality of vanes 13 to 18 are provided for this purpose. These vanes are integral with the inner walls of the chamber 9 and serve to form a channel in which the ball 10 may rise and fall. As shown more particularly in Fig. 2, the six vanes are spaced on opposite sides of the ball 10 and are of such shape as to offer little opposition to the flow of the water from pipe 11 up and around ball 10 and out pipe 8, the direction of flow of the water being indicated by the arrows. It will also be noted by an examination of Fig. 2 that considerable side play of the ball 10 is permissible in spite of the vanes. The amount of side play, however, should not be sufficiently great to endanger the complete and prompt closing of pipe 11 each cycle.

The type of ball valve and chamber just

described is particularly adapted for use in pumps intended to work with water containing an appreciable amount of solid matter and sediment, such as sewage containing 5 rags, hair, string, etc. The entire interior of the ball chamber 9 is designed to present only smooth surfaces to the flow of the dirty water and consequently there is a minimum opportunity offered for the catching 10 or deposit of solid matter in the ball chamber. It should be particularly noted that the vanes 13 to 18 are rounded off smoothly on all sides so as to offer no sharp projections in the path of the water flow. Also 15 the vanes are of comparatively short length, extending along the side walls for a length less than the radius of ball 10. It should also be pointed out that there are no projections located between the ball and the 20 cover 19 of the ball chamber, so that there is a free passage for the water above the ball. The cover 19 may be made removable in any desired manner so that the ball valve may be periodically inspected. The character 25 of the ball chamber just described is such that the cover 19 may be hinged to the main part of the pump, thereby enabling the ball chamber to be readily opened without any danger of having the cover cast 30 aside in the dirt by careless workmen as would be possible with an unhinged cover. It is, of course, important that the joint between the cover and the ball chamber should be clean and air tight.

35 One manner in which the cover 19 may be hinged is illustrated in Fig. 3, wherein the cover 19 is shown pivotally connected at the point 21 with an acute angle member 22 which is hinged at one end to the point 23. 40 The other end is slotted to receive a threaded rod 25 hinged at the point 24. A nut 26 may be screwed down on rod 25 against member 22 whereby an air tight joint may be secured between cover 19 and the walls 45 of chamber 9.

This type of ball chamber has been found by actual experiment to give far more satisfactory results than types heretofore employed for the pumping of dirty water 50 which tends to render the ordinary ball valve inoperative due to the accumulation of dirt caught by any sharp projections in the ball chamber.

With the exception of the ball chamber 55 described above, the pump may be constructed in any well-known manner and size

of suitable materials. The invention is also not to be construed as limited to any particular number of vanes or location, being mainly concerned with the absence of rods 60 or sharp projections in the ball chamber.

It is also to be understood that this invention is capable of embodiments differing widely from the form described in detail above, without departing in anywise from 65 the spirit of this invention as defined in the appended claims.

The invention claimed is:

1. A ball valve for a pump used in pumping water containing a large amount of 70 solid matter and comprising a chamber, a ball in said chamber, an intake at the bottom of said chamber, said intake being closed at times by said ball, said ball being adapted to be periodically lifted from said 75 intake whereby water from said intake may be forced into said chamber, an outlet for said chamber, and a plurality of elongated ridges spaced around said ball and integral 80 with the walls of said chamber for guiding said ball, said ridges being parallel to each other and parallel to the direction of movement of said ball, said ridges being smoothly rounded on their sides and ends and other surfaces to offer no sharp projections in the 85 water passage, the remainder of the interior of said chamber being free of sharp projections which would tend to impede the passage of solid matter in the water being pumped. 90

2. A ball valve for a diaphragm pump comprising a chamber, a ball in said chamber, a pipe forming a part of the bottom of said chamber, the end of said pipe being closed at times by said ball, said ball being 95 adapted to be periodically lifted from said pipe, whereby water from said pipe may be forced into said chamber, an outlet for said chamber on one side thereof, and vertical 100 parallel vanes on two of the remaining sides of said chamber for guiding said ball, said vanes being smoothly rounded on their sides and ends to offer no sharp projections in the water passage, the remainder of the interior of said chamber being free of sharp projections which would tend to impede the passage of solid matter in the water being pumped. 105

In witness whereof, I hereunto subscribe my name this 14 day of July A. D., 1925.

ALFRED S. MARLOW.
